(57) **CLAIM**

The ornamental design for a desktop toy magnet with
pivotable top half, as shown and described.

DESCRIPTION

FIG. 1 is a perspective view of a desktop toy magnet with
pivotable top half, showing my new design;

FIG. 2 is a front view thereof;

FIG. 3 is a rear view thereof;

FIG. 4 is a rightside view thereof;

FIG. 5 is a leftside view thereof;

FIG. 6 is a top view thereof; and,

FIG. 7 is a bottom view thereof.

The broken lines in the drawings illustrate portions of the
desktop toy magnet with pivotable top half that form no part
of the claimed designs; in particular, a base of the desktop
toy magnet with pivotable top half is presented in broken
lines.
